UNITED STATES PATENT OFFICE.

WILLARD I. TWOMBLY, OF NEW YORK, N. Y.

LIQUID-FEEDING MEANS AND PUMP.

Application filed March 27, 1920. Serial No. 369,379.

To all whom it may concern:

Be it known that I, WILLARD I. TWOMBLY, a citizen of the United States, and resident of New York city, in the county of New York and State of New York, have invented certain new and useful Improvements in Liquid-Feeding Means and Pumps (Case C), of which the following is a specification.

10 This invention relates to means for feeding liquid, as for instance, liquid fuel or gasoline from a source of supply to a reservoir and to the intake of an engine such as the carburetor of an internal combustion engine.

15 The device, as shown herein, is adapted for the same general purposes, and embodies, in a new way, certain of the features of construction and operation set forth in 20 my prior application, Serial No. 197,589, filed October 20th, 1917.

25 The general purpose of the invention is to provide improved liquid pumping means operable from the movements of the engines, which means are simple and cheap in construction and efficient in operation.

30 Heretofore in apparatus of this character, it has been the practice to connect a reservoir to the intake manifold of an engine and to utilize the suction of the piston of the engine to apply a vacuum directly to the surface of the fuel in the reservoir. There have also been attempts to employ a diaphragm pump directly connected but 35 such attempts have been practical failures for many reasons which will become evident from a consideration of my practical, fool-proof device herein disclosed.

35 One object of this invention is to provide 40 a pump having a pump element operable by a wide range of varying pressures and speeds of the engine; and an important feature is employing as the pumping element, a projectile or freely movable, spring 45 returned piston.

45 The pump is preferably associated with a reservoir having the pump located therein and preferably extending therethrough. Preferably the reservoir is cylindrical and 50 has the pump cylinder axially disposed therein, the pump cylinder is vertically arranged; preferably the intake for the liquid opens upwardly into the lower end of the cylinder; the outlet into the reservoir is 55 through the lateral wall of said cylinder; and the inlet for application of pressure

from the combustion chamber of the engine, is through a constriction at the upper end of said cylinder. Preferably the pump cylinder is rigidly secured water-tight, through 60 the bottom of the reservoir and the upper end of the pump projects through and serves as securing means for clamping the cover or closure on said vessel.

Several important features of the invention relate to making it successfully operative under certain conditions likely to arise in practical operation of the device. Under certain conditions, there will be no liquid in the supply line, as for instance, 65 when the tank has become empty, or the pump valves have leaked. To meet such conditions it is important the pump be able to act effectively as an air pump to vacuumize the line and draw up the liquid, and, 70 for subsequent successful operation at high speeds of the engine, it is necessary that the last remnants of air be expelled from the pump cavity so that the piston will act on an incompressible body of fluid, namely, all 75 liquid, without any trapped air or gas.

For effective air pumping the inlet valve into the pump chamber is preferably an upwardly-opening, gravity-seated ball, and, in order to avoid trapping air, the inlet passage 80 opens upwardly.

The port through which the liquid is expelled from the pump cavity and the outlet valve therefor have certain peculiarities particularly adapting them to serve both 90 the above purposes. The outlet port opens upwardly from the topmost portion of the pump cavity which, in this case, is the pump face of the piston, so that any air or other gas rising to the top of the liquid, will be 95 automatically pumped out and expelled into the reservoir, thus leaving only incompressible liquid for action of the pump at high speeds.

100 Preferably, the outlet valve is also located in the piston and is arranged to lift and seat in alignment with the reciprocating movements of the piston, so that the inertia of the outlet valve is caused to assist in seating it at the end of each expelling 105 outstroke and beginning of the lifting return-stroke of the piston, and in unseating it at the end of each lifting stroke and beginning of the expelling stroke.

110 The higher the speed of the piston and the more sudden the starts and stops of the strokes, the more powerful this inertia effect.

will become. This inertia effect may be very great in the present case because the piston is a projectile or flying piston, the speeds of which are free from control by any rigidly acting driving connection, and the starts and stops must occur as often as 5 times per second, for idling speeds, up to say 80 to 100 or more times per second, for high speeds. Moreover, the self- 10 seating inertia effect will be greatest when it is most needed, that is, when the engine speeds are highest, and also when the piston is pumping air. The air is relatively inefficient for seating and unseating the valve, 15 but since it affords enormously less resistance to the piston, it promotes higher piston velocities, thereby making inertia more effective in its seating and unseating action.

The level of liquid is governed by a float 20 operating a throttle valve which controls the motive fluid connection and which preferably operates on the constricted portion of the inlet passage so that little power is required to control high pressures. More- 25 over, the entire throttle control apparatus, including float, linkage, valve and the part of the motive fluid conduit controlled by the latter are all within the reservoir so that no 30 passages for movement of the valve and its working connections, are exteriorly opening.

Other objects and advantages will herein- 35 after appear.

In the drawings accompanying and forming 40 a part of this specification

Figure 1 is a diagrammatic view showing an embodiment of my invention applied to a motor vehicle utilized to lift gasoline from a tank and deliver it to the carbureter of an engine, the tank being located at a point below the carbureter;

Figure 2 is a sectional side elevation of an embodiment of a pumping mechanism combined with a reservoir for use in connection with my improved fuel or gasoline feeding 45 means;

Figure 3 is a plan detail of the float controlled throttle mechanism; and

Figure 4 is a sectional detail of the motive pressure connection with the combustion 50 chamber of a cylinder of the engine.

In Figure 1 of the drawings, I have shown an embodiment of my invention applied as a fuel or gasoline feed in connection with a motor vehicle, the motive power of which is 55 the usual variable-throttle, variable-speed internal combustion engine 9 to which is connected a carbureter 10 by a manifold 11. A fuel or gasoline supply tank 12 located at the rear of the vehicle at a point below the 60 carbureter, with my improved means (designated in a general way by P) to draw the fuel from the tank and deliver it to the carbureter of the intake of the engine in position between said tank and carbureter, the 65 tank being connected thereto by a pipe 13

and the carbureter by a pipe 14; said means to draw fuel from the tank and deliver it to the carbureter is connected by a pipe 15 to the combustion chamber of the engine, such as the opening in a cylinder wall of the engine, as shown at 16.

The means to draw and deliver the fuel from the tank to the carbureter or engine is operable by the varying pressures in the combustion chamber of the engine, such as 75 during the power and compression strokes, or the suction and exhaust strokes, of the engine piston, and in the form thereof shown in Figure 2, includes a reservoir 29.

The reservoir 29 is preferably a cylindri- 80 cal, drawn metal cup, in which the pumping mechanism is axially located, said reservoir having an outlet 34 to which the pipe 14 leading to the carbureter is connected. The reservoir is closed by a cover 36 having an 85 annular flanged groove 37 to engage the upper edge 35 of the receptacle. The cover has a central opening through which the pump extends and the cover is caused to forcibly engage the edge 35 of the reservoir to prevent leakage by the splashing of the fuel in the reservoir by means of nut 21a screw-threaded on the projecting end of the pump. Thus the pump serves somewhat as a centering stud and as a clamping bolt to secure the 90 cover on the reservoir.

The pump comprises a cylinder 17 in which there is mounted a reciprocable piston 18, said piston separating the cylinder into a motive chamber 19 and a pump chamber 20. The motive chamber has a motive fluid inlet 23 through the removable closure 21 of the cylinder 17 and to the threaded projection of this closure 21, is connected the pipe 15 whereby the motive chamber has 105 a conduit connection with the combustion chamber of the engine cylinder. It will be noted that the motive pressure inlet 23 has a constricted portion 23a of extremely small diameter as compared with that of the pump 110 chamber, say $\frac{1}{32}$ inch for a $\frac{1}{2}$ inch pump chamber. This would make the cross-sectional area of the cylinder 400 times that of the constriction, but it will be understood that this may be varied to suit the conditions 115 and purposes in view.

The pump chamber 20 has an inlet 24, connected through a coupling and pipe 13, with the tank 12, the inlet opening upward into the pump chamber 20 and being normally 120 closed by an upwardly-opening gravity-seat- ed valve 26.

The piston 18 is usually formed to fit the pump cylinder 17 closely enough so that no 125 packing is necessary, an easy sliding fit with a clearance of one to two thousandths inch being sufficient to operatively withstand the pressures in the motive chamber, 19. If desired, however, the piston may be provided with a cup leather packing 40 clamped be- 130

tween the piston and a flanged head 41 threaded on to a projection 42 carried by the piston. The piston body is preferably made of great length as compared with its 5 diameter so that there can be no tendency for it to become cocked in the cylinder even when reciprocating most violently.

The pump end of the piston is preferably formed with an outlet 27 for discharge of 10 the pump fluid and the outlet valve 30 is preferably located in the piston for reasons explained above. A convenient way of forming the pump end of the piston is to drill it axially from the lower end to a diameter 15 suitable for the chamber of the outlet valve 30 with sufficient clearance for flow of fluid around the sides of the valve. Then the spring 33 and valve 30, which is preferably a ball, being inserted, a screw 20 bushing 31 formed with a valve seat and port is screwed in behind the ball. Preferably a spring 33 is provided to press the valve 30 toward its seat. The upper portion 25 of the outlet valve chamber 27^a is provided with outlet ports 27^b drilled through the walls of the piston. As these ports are in, and necessarily travel with the piston, a wide annular groove 27^c is formed outside the piston, the width of the groove being 30 such that during normal operation, some portion of it will always register with ports 27^d which are drilled through the wall of the pump cylinder, preferably at a downward slant so that the discharge of the 35 liquid into the reservoir will be downward. By varying the width of groove 27^c, the limit of the piston stroke may be controlled, since movement of the piston to a position where the ports 27^d are covered, cuts off 40 further escape of liquid from the pump cavity.

It will be noted that in this piston, the pumping or liquid-sucking surface comprises the lower surfaces of piston 18, bushing 31 and ball 30, while the liquid expelling surface is the upper surface of groove 27^c and the top of drill hole 27^a. Also that similar functions could be served by other constructions affording the necessary relations of liquid-sucking and expelling surfaces with interspace containing the outlet and outlet valve.

The piston is yieldingly maintained toward the uppermost end of the cylinder 17 55 by a long spring 43. This spring is compressed by the piston on the compression and explosion strokes of the engine cylinder and serves to return the piston when the pressure in the motive cylinder decreases 60 during the exhaust and suction strokes.

During high pressure strokes of the piston of the engine, the pressure will be transmitted through the connection 15 to the motive chamber 19 of the pump cylinder 17, 65 from the combustion chamber of the engine

cylinder, and will be exerted on the end of the piston 18, and through the latter on the fluid in the pump chamber. This will seat the inlet valve 26 and unseat the outlet valve 30 thereby cutting off the tank and 70 opening communication between the pump chamber 20 and the reservoir 29. During the suction strokes of the engine piston with the consequent reduction of the pressure in the connection 15 and in the motive chamber 75 19, the spring 43 will move the piston toward the upper end of the motive chamber, and, the valve 30 having automatically seated by gravity, inertia and spring 33, the return movement of the piston 18 will create 80 a vacuum in the pump chamber 20, thereby unseating the valve 26 and drawing the fuel from the tank 12, through the connection 13, into the pump chamber. This latter movement of the piston 18 may also be facilitated 85 during the suction stroke of the piston of the engine by the creating of a vacuum in the motive chamber.

Where the speed of operation of the engine is fairly uniform or is not too fast, as 90 for instance, on certain types of stationary engines, the spring may be made strong enough so that the return stroke of the pump piston will always be completed.

For the preferred use on automobile engines, however, the spring 43 is preferably made yielding enough to permit a substantial pumping stroke even when the pressures in the engine cylinder are weak, as 95 for instance, when idling with nearly closed 100 throttle or when the engine is being cranked. Such a spring becomes progressively stiffer when increasing engine pressures give longer outstrokes of the pump piston. I have discovered, however, that 105 this spring may be made more yielding and more sensitive for the light pressure, when employed in conjunction with a supplemental stiff spring 43^a which, as will be seen from the drawings, is of substantially 110 shorter length and range of action. With this arrangement, spring 43 may be made only so stiff as is necessary to lift the load of gasoline in the supply line at slow speeds, and spring 43^a need not function at all when 115 the pressures are low and the stroke is short; but when the motive pressures become more violent and the stroke longer, spring 43^a will afford a supplemental increasing resilient restoring power addition 120 to that obtained by the increasing compression of spring 43. Obviously, several supplemental springs of progressively decreasing length and range of action can be employed, if desired. Also it would be quite 125 possible to design a single spring adapted to act like my two springs except for the technical difficulties and expense involved.

At the motive end of the piston is a bumper spring 44 of shorter length and 130

range than those just described, it is interposed between the piston and the closure end 21 of the motive chamber, to prevent the upper end of the piston from striking against the end of the chamber and making clicking or knocking noises. When it strikes the end of the chamber, it is compressed and its subsequent recoil and expansion assists the next out-stroke.

- 10 The reciprocation of the piston 18 synchronizes with the suction and compression strokes of the engine piston, and the stroke of the piston 18 is regulated in accordance with the pressure in the engine cylinder.
- 15 For instance, should the throttle valve for the fuel intake of the engine be closed with consequent low pressures in the engine cylinder there will be a low pressure in the motive chamber of the cylinder 17 and a
- 20 short motion or out-stroke of the piston 18, and as the throttle valve for the engine intake is opened with the consequent increase of pressures in the engine cylinder, there will be a corresponding increase of
- 25 the pressures in the motive chamber of the cylinder 17 and a longer out-stroke imparted to the piston 18.

It will be evident, however, that spring 43, and 43^a which will be yielding enough 30 to permit efficient pumping movement of the piston for the lower and medium pressures and speeds of the engine, will function somewhat differently when the engine is operated at high speed. Such a spring 35 can complete the return stroke in the motive pressure is relatively low so as to give short out-strokes and if the speed of the engine is slow so as to give the spring time to do its work. But where high engine pressure, 40 giving a long out-stroke, is combined with high engine speed giving a short time for the spring to work, there will be only time enough for a portion of the return stroke, the slower final part of said stroke being 45 cut short by a succeeding explosive pressure. Consequently, with increasing pressures and speeds, the piston continues to reciprocate in response to the variations of pressure, and the length of the stroke may 50 be approximately the same or may be less, but the range of the stroke tends to shift toward the spring to a position where the spring operates under a uniformly increased range of maximum and minimum pressures.

There may be a similar effect due to the above described constriction of the inlet passage at 23^a. This constriction serves to moderate on the pump piston, the violence 60 of the engine explosions, but it also tends to average up the low pressures as well as to average down high pressures, and this tendency becomes more pronounced with increasing speeds of the engine. Hence 65 though the pressures in the engine cylinder

continue to alternate between pronounced vacuum and high pressure even at high speeds, the pressures on the pump piston will become pulsating, that is, they are above atmosphere even during the vacuum 70 strokes of the engine. This pulsating excess pressure at high speeds also tends to force the pump piston toward the spring thereby compressing the spring until a position is reached where the spring is under 75 a continuous minimum compression equal to the continuous minimum pressure in the motive chamber.

The piston continues to reciprocate in response to the variations of pressure, and the length of the stroke may be approximately the same or may be less, but the range of the stroke is shifted enough to make the spring return strokes more powerful and therefore quicker acting. 85

Making the spring 43 of great length and providing a long clearance or pumping space in the cylinder, as shown in the drawings, affords a considerable range for the above described shift of position of the stroke of the piston and corresponding increase of spring stiffness. It is one good method of rendering the device automatically self-accommodating for the wide range of engine speeds and pressures practically necessary in the operation of automobile and similar internal combustion engines. For a considerable range of engine speeds the length of the stroke will be determined by the differences of pressure during each cycle of explosion, exhaust, suction and compression in the engine, changes in the speed being taken care of to a large extent by the automatic shift of the position of the stroke to a position 100 where the spring is quicker acting. 105

The spring 44 on the opposite end of the piston, is of shorter length and shorter range of action than spring 43. It functions only when conditions are such as to permit complete return stroke of the piston on each suction stroke of the engine and this, as will be evident, is at the lower engine speeds and pressures, particularly at times when the speeds and pressures are 115 low enough for establishing a vacuum, or below-atmosphere, pressure in the motive chamber of the pump during each suction stroke of the engine. At such times the spring 44 is compressed by the suction 120 stroke of the piston. Then, as soon as the suction is relieved, the expansion of spring 44 initiates and assists the subsequent expansion stroke. In this way the short spring 44 acts during times of alternating 125 suction and pressure on the piston, in a manner somewhat analogous to the action of spring 44 during times of continuous pulsating pressure.

The inlet and its valve and the outlet and 130

its valve have peculiarities which in combination contribute to the efficiency of the pump, especially when used for its preferred purpose as a fuel pump on an automobile engine.

5 The explosion strokes in any one of the cylinders of an automobile engine will vary from say 3 or 4 per second for idling, up to say 40 or 50 or more per second for high speed operation. Obviously, in such operation, any 10 delay, even for a small fraction of a second, in the closing of the inlet valve will permit appreciable slip or backflow of liquid to the tank.

The effectiveness of inertia in seating the 15 outlet valve under such conditions has been explained above. The cooperating inlet valve 26 is a free, gravity-seated ball. It is a simple and very effective means of getting the quick free, low-resistance opening of the 20 inlet which is very desirable at all times, and particularly so when the supply pipe is empty and the gasoline must be lifted by first pumping air; but the ball form and absence of spring pressure tend to make it 25 slow-closing. Hence the outlet 27 is of smaller diameter and of greater fluid flow resistance, than the supply inlet 24; also the piston outlet valve is forced to closed position by spring 33. The smaller size of the 30 outlet port and the spring pressure on the valve both contribute to making the outlet of higher resistance than the inlet. This gives a back-pressure on the outlet, with the result that the high speed movement of the piston 35 under the explosive pressure from the engine, taking effect on incompressible liquid, piles up a sufficient back-pressure on the inlet valve to force it tight down on its seat at the very beginning of the expelling stroke of 40 the piston.

The operation of the pump is regulated by a throttle valve in the motive pressure inlet to the pump cylinder. This is preferably 45 a needle valve 50 operating to open and close the pressure inlet end of the above described constriction 23^a. Preferably, the constriction is drilled horizontally as shown and the needle valve plays horizontally in a passage drilled in the casting at a point opposite the 50 open end thereof.

This needle valve may be operated to maintain constant level in the reservoir by a float 32 encircling the pump cylinder. The 55 float rises and falls with the rise and fall of liquid in the reservoir and this motion is transmitted to the throttle valve by means of vertical members, preferably stiff wires 51, secured vertically in the float. Their upper ends are turned at right angles to form 60 pivots 52 with anti-friction thrust collars 53 thereon. These pivots engage the U-shaped lever 54 from the outsides of the legs thereof. This lever is pivoted to the pump structure by fulcrum pivot studs 55. The movements 65 of lever 54 are transmitted to the needle

valve by a power-multiplying connection consisting of studs 56 riveted at 57 and forming pivots for links 58, 58, pivoted on studs 59 on member 60. The links 58 may be held on their studs by cotter pins 61, 61, 62, 70 62. The member 60 is internally screw-threaded on the outer end 63 of needle valve 50. The position of the needle valve may be adjusted for proper operation in connection with constriction 23^a by screwing it in or 75 out and then securing it in position by nut 64.

Preferably the studs 51 are sprung into engagement with the lever 54 and are held there merely by their resilient stiffness. The 80 engagement with studs 55 may be similarly maintained by resilient pressure of the legs of lever 54 or, if desired, the outer ends may be slightly upset.

While the motive power connection with 85 the engine may be through the opening ordinarily employed for the priming cup, I prefer the arrangement shown in Figure 4 where the opening 70 is tapped through the side of the cylinder at a point below the uppermost limit of movement of the piston 71. A nipple 72 is screwed in and the pipe 15 secured thereto by union 73. Where the above described pumping apparatus is to be used for supplying gasoline to the carburetor 90 of the engine, pressure and vacuum conditions in the reservoir are usually undesirable. Hence, I have shown grooves 80 pressed in the top of the reservoir closure and communicating with the interior through the 100 central perforation therein.

In practical operation, it is important to have the location of the pump cylinder within and in contact with the body of gasoline and to have the normal level of the latter 105 maintained substantially above the level of the pump outlets. Thus designed, the gasoline keeps the pump cool thereby dissipating the unavoidable heat transmitted through the pressure connection with the 110 combustion chamber of the engine which would otherwise tend to vaporize the gasoline in the pump. As it is, the pump chamber is kept flooded and primed with gasoline substantially free from vapor and hence in 115 condition for immediate effective pumping operation.

I claim:

1. In a fluid supply system, an internal combustion engine, in combination with a 120 pressure operated pump including a piston actuated by fluid pressure from the combustion chamber, said piston operating to apply alternating pressure and suction in the pump chamber; inlet and outlet passages and check valves therefor controlling the flow of fluid; one of said passages and the check valve therefor being carried by the piston and the check valve being arranged to move in alignment with the re- 125 130

- 6
3 iprocating movements of the piston, so that the inertia of the valve operates to assist the lifting and seating movements thereof.
2. In a fluid supply system, an internal combustion engine, in combination with a pressure operated pump including a piston actuated by fluid pressure from the combustion chamber, said piston operating to apply alternate pressure and suction in the pump chamber; inlet and outlet passages and check valves therefor controlling the flow of fluid; said outlet being through the pump head of the piston and said outlet valve being located in the piston and arranged to move in alignment with the reciprocating movements of the piston, so that the inertia of the valve operates to assist the lifting and seating movements thereof.
3. In a fluid supply system, an internal combustion engine, in combination with a pressure operated pump including a piston actuated by fluid pressure from the combustion chamber, said piston operating to apply alternate pressure and suction in the pump chamber; inlet and outlet passages and check valves therefor controlling the flow of fluid; said outlet being through the pump head of the piston and said outlet valve being a ball located in the piston and arranged to move in alignment with the reciprocating movements of the piston, so that the inertia of the ball operates to assist the lifting and seating movements thereof.
4. In a fluid supply system, an internal combustion engine, in combination with an upright, pressure operated pump including a piston having its downward stroke non-positively actuated by a fluid pressure from the combustion chamber of a cylinder of the engine and its return stroke assisted by a spring, the pump surfaces of said piston constituting the top of the pump chamber; inlet and outlet passages and check valves therefor controlling the flow of fluid; said outlet being through said pump surface of the piston.
5. In a fluid supply system, an internal combustion engine, in combination with an upright, pressure operated pump including a piston having its downward stroke non-positively actuated by a fluid pressure from the combustion chamber of a cylinder of the engine and its return stroke assisted by a spring, the pump surfaces of said piston constituting the top of the pump chamber; inlet and outlet passages and check valves therefor controlling the flow of fluid; said outlet being through said pump surface of the piston and arranged to move in alignment with the reciprocating movements of the piston, so that the inertia of the valve operates to assist the lifting and seating movements thereof.
6. In a fluid supply system, an internal combustion engine, in combination with an upright, pressure operated pump including a piston having its downward stroke non-positively actuated by a fluid pressure from the combustion chamber of a cylinder of the engine and its return stroke assisted by a spring, the pump surfaces of said piston constituting the top of the pump chamber; inlet and outlet passages and check valves therefor controlling the flow of fluid; said outlet being through said pump surface of the piston, said outlet valve being assisted by a float and connecting lever mechanism for opening and closing the motive connection; and a valve for opening and closing the motive connection; and a float and connecting lever mechanism for 130
7. In a fluid supply system, an internal combustion engine, in combination with an upright, pressure operated pump including a piston having its downward stroke non-positively actuated by a fluid pressure from the combustion chamber of a cylinder of the engine and its return stroke assisted by a spring, the pump surfaces of said piston constituting the top of the pump chamber; inlet and outlet passages and check valves therefor controlling the flow of fluid; said outlet being through said pump surface of the piston, said inlet and inlet valve opening upwardly into the lower part of said pump chamber.
8. In a fluid supply system, an internal combustion engine, in combination with an upright, pressure operated pump including a piston having its downward stroke non-positively actuated by a fluid pressure from the combustion chamber of a cylinder of the engine and its return stroke assisted by a spring, the pump surfaces of said piston constituting the top of the pump chamber; inlet and outlet passages and check valves therefor controlling the flow of fluid; said inlet and inlet valve opening upwardly into the lower part of said pump chamber, said outlet being through said pump surface of the piston and said outlet valve being located in the piston and arranged to move in alignment with the reciprocating movements of the piston, so that the inertia of the valve operates to assist the lifting and seating movements thereof.
9. In a fluid supply system, an internal combustion engine, in combination with a combined reservoir and pump, said pump including a reciprocating piston element having a working head in operative relation to the pump chamber and a motive head connected with the combustion chamber of a cylinder of the engine and operable by the varying pressures therein; a valve for opening and closing the motive connection; and a float and connecting lever mechanism for 130

opening and closing said valve by movements of said float; said reservoir enclosing said pump, valve, lever mechanism and float.

5 10. In a fluid supply system, an internal combustion engine, in combination with a combined reservoir and pump, said pump including a reciprocating piston element having a working head in operative relation to the pump chamber and a motive head connected with the combustion chamber of a cylinder of the engine and operable by the varying pressures therein; a constricted passage in the motive pressure connection at the pump end thereof; a valve operating at said constriction to open and close communication therethrough; and a float and connection lever mechanism for opening and closing said valve by movements of said float; 20 said reservoir enclosing said pump, valve, lever mechanism and float.

11. In a fluid supply system, an internal combustion engine, in combination with a reservoir and upright pump located centrally thereof; said pump including a reciprocating piston element having a working head in operative relation to the pump chamber and a motive head connected with the combustion chamber of a cylinder of the engine and operable by the varying pressures therein; a valve for opening and closing communication through said passage, a float encircling said pump and guided thereby; connecting lever mechanism for opening and closing said valve by movements of said float and a reservoir enclosing said pump, valve, lever mechanism and float.

40 12. In a fluid supply system, an internal combustion engine, in combination with a reservoir and upright pump located centrally thereof; said pump including a reciprocating piston element having a working head in operative relation to the pump chamber and a motive head connected with the combustion chamber of a cylinder of the engine and operable by the varying pressures therein; a constricted passage in the motive pressure connection arranged horizontally at the pump end thereof, a plunger valve operating on the pressure receiving end of said constricted passage; a float encircling said pump and guided thereby; connecting lever mechanism for opening and closing said valve by movements of said float and a reservoir enclosing said pump, valve, lever mechanism and float.

60 13. In apparatus of the class described, an internal combustion engine in combination with a pump of the vertical type including a piston, the upper face of which is connected through a valve with the combustion chamber of a cylinder of said engine and actuated by the alternating pressures therein and the lower face in operative relation to

a pumping chamber provided with suitable inlet and outlet passages and valves; and springs acting oppositely on said piston, and differently for different portions of the range of stroke thereof.

70 14. In apparatus of the class described, a variable-throttle, variable-speed engine in combination with a pump of the vertical type having a pumping element, the upper face of which is connected through a valve with the pressure chamber of a cylinder of said engine and actuated downwardly by the varying pressures therein; the lower face of said pump element being in operative relation to a pumping chamber provided with suitable inlet and outlet passages and valves; a spring on the pump side of said pumping element compressing on the pressure actuated movement of said pumping element and expanding on return movement thereof; and another spring on the motive side of said pumping element, of shorter length and range than said first mentioned spring, for the purpose described.

75 15. A variable-speed engine in combination with a pump of the vertical type for utilizing varying pressure conditions in the pressure chamber of a cylinder of the engine, said pump including a floating piston having a lower working portion in operative relation to the pump chamber and an upper motive portion in operative relation to a motive chamber; a valve for controlling application of the pressure variations of the latter upon the former; an inlet and non-return valve therefor controlling free, low-resistance flow of fluid toward said pump chamber; an outlet and non-return valve controlling a relatively high resistance flow of fluid away from said pump chamber; a conduit connecting the motive chamber of the pump with the pressure chamber of a cylinder of the engine whereby at low speeds of the engine the alternating vacuum and high pressure conditions of the engine cylinder produce modified vacuum and high pressure conditions in the motive chamber of the pump, and, at high engine speed, produce pulsating pressures higher than atmosphere in the motive cylinder of the pump; a long spring at the pump end of the piston to oppose the expansion strokes and assist the return strokes; and a shorter spring at the motive end of the piston to cushion vacuum strokes and assist expansion strokes.

80 16. In apparatus of the class described, a variable-pressure, variable-speed engine, in combination with a pump including a piston, one face of which is directly connected with the pressure chamber of a cylinder of said engine and actuated by the varying pressures therein and the other face in operative relation to a pumping chamber provided with suitable inlet and outlet pas-

sages and valves; a spring on the pump side of said piston pressing thereon throughout the entire range of its movement; and another spring acting on said piston in the 5 same direction but of shorter length and range than said first mentioned spring, for the purpose described.

17. In apparatus of the class described, an internal combustion engine in combination 10 with a pump having a pumping element, one face of which is directly connected with the combustion chamber of a cylinder of said engine and actuated by the alternating pressures therein; the other face of said 15 pump element being in operative relation to a pumping chamber provided with suitable inlet and outlet passages and valves; a spring pressing the piston toward the pressure inlet throughout the entire range of piston movement; a supplemental stiffer spring of shorter length and range but acting in the same direction; and a third spring of yet shorter length and range acting in the opposite direction to cushion return 20 strokes and assists initiating the out-strokes of the piston.

18. A source of pressure variations of varying rates and intensities, in combination 30 with a vessel adapted to be secured in upright position, a closure for said vessel, a tubular member secured in vertical position in said vessel and having inlet passages from the exterior through its upper and lower end portions respectively, a combined 35 motor and pump piston actuated by pressures applied from said source through the upper inlet passage and a spring in the pump chamber; the intake of said pump being through said bottom passage and the 40 discharge being through an intermediate outlet into said vessel, the lower end of said tubular member being rigidly secured through the bottom of said vessel and the upper end projecting through said closure, 45 together with an exterior member screwed on said tubular member to clamp said closure on said vessel and a valve for controlling said inlet.

19. A source of pressure variations varying 50 in rates and intensities, in combination with a vessel adapted to be secured in upright position, and a tubular member including a pump barrel, secured in vertical position in said vessel, a piston in said pump 55 barrel dividing it into an upper motive chamber and a lower pump chamber, the intake of said pump chamber being through a gravity seated valve at the bottom of said tubular member, the outlet being through 60 an intermediate portion, the inlet for the motive fluid to the piston being through the top of said tubular member and a valve for controlling said inlet.

20. In liquid feeding means for internal 65 combustion engines, the combination with

an internal combustion engine and a liquid supply tank, of a conduit and pressure actuated pump of the upright type interposed between the tank and the intake of the engine; said pump including a cylinder and a 70 piston to reciprocate in said cylinder and separating the cylinder into a pump chamber and a motive chamber one at a higher level than the other; a port and conduit connecting the motive chamber with the engine 75 cylinder; a valve for controlling application of the pressure variations of the latter upon the former; a spring in the pump chamber yieldingly pressing said piston toward said port; an upwardly opening valve controlled 80 inlet into the pump chamber, from the tank; a pump outlet opening upwardly from the uppermost portion of the pump chamber; and a non-return valve adapted to check reverse flow of liquid through said outlet during 85 the lifting stroke of said piston.

21. In liquid feeding means for internal combustion engines, the combination with an internal combustion engine and a liquid supply tank, of a conduit and pressure actuated pump of the upright type interposed between the tank and the intake of the engine; said pump including a cylinder and a 90 piston to reciprocate in said cylinder and separating the cylinder into a pump chamber and a motive chamber one at a higher level than the other; a port and conduit connecting the motive chamber with the engine cylinder; a valve for controlling application 95 of the pressure variations of the latter upon the former; a spring in the pump chamber yieldingly pressing said piston toward said port; an upwardly opening valve controlled inlet into the pump chamber from the tank; a pump outlet opening upwardly from the 100 uppermost portion of the pump chamber; and a non-return valve adapted to check reverse flow of liquid through said outlet during the lifting strokes of said piston; said motive chamber port being constricted and 105 said spring and pump chamber being substantially longer than the normal pressure-actuated out-strokes of the pump piston, as 110 for the purpose described.

22. In a fluid supply system, a source of 115 gaseous pressure variations, in combination with a pressure operated pump including a floating piston actuated by said gaseous pressure variations, said piston operating to apply alternate pressure and suction in the 120 pump chamber; inlet and outlet passages and check valves therefor controlling the flow of fluid; said outlet being through the pump head of the piston and said outlet valve being located in the piston and arranged to move in alignment with the reciprocating movements of the piston, so that the inertia of the valve operates to assist the lifting and seating movements thereof.

23. In a fluid supply system, a source of 130

- gaseous pressure variations, in combination with a pressure operated pump including a floating piston, actuated by said gaseous pressure variations, said piston operating to 5 having a working head in operative relation to the pump chamber and a motive head connected with the pressure chamber of a cylinder of the engine and operable by the varying pressures therein; a valve for opening and closing communication through said passage; a float encircling said pump and guided thereby; connecting lever mechanism for opening and closing said valve by movements of said float; and a reservoir enclosing 60 said pump, valve, lever mechanism and float.
- 5 apply alternate pressure and suction in the pump chamber; inlet and outlet passages and check valves therefor controlling the flow of fluid; said outlet being through the pump head of the piston and said outlet valve being located in the piston and arranged to move in alignment with the reciprocating movements of the piston, so that the inertia of the valve operates to assist the lifting and seating movements thereof, and a spring 10 yieldingly pressing said outlet valve toward its closed position.
24. In a fluid supply system, a source of gaseous pressure variations, in combination with an upright, pressure operated pump including a floating piston having its downward stroke non-positively actuated by pressure variations from said source and its return stroke assisted by a spring, the pump surfaces of said piston constituting the top 15 of the pump chamber; inlet and outlet passages and check valves therefor controlling the flow of fluid; said inlet and inlet valve opening upwardly into the lower part of said pump chamber; said outlet being 20 through said pump surface of the piston and said outlet valve being located in the piston and arranged to move in alignment with the reciprocating movements of the piston, so that the inertia of the valve operates to assist 25 the lifting and seating movements thereof; and a yielding spring pressing downwardly on said outlet valve, for the purpose described.
25. In a fluid supply system, an engine, in combination with a combined reservoir and pump, said pump including a reciprocating piston element having a working head in operative relation to the pump chamber and a motive head connected with the pressure 30 chamber of a cylinder of the engine and operable by the varying pressures therein; a valve for opening and closing the motive connection; and a float and connecting lever mechanism for opening and closing said 35 valve by movements of said float; said reservoir enclosing said pump, valve, lever mechanism and float.
26. In a fluid supply system, an engine, in combination with a reservoir and upright 40 pump located centrally thereof; said pump including a reciprocating piston element
- having a working head in operative relation to the pump chamber and a motive head connected with the pressure chamber of a cylinder of the engine and operable by the varying pressures therein; a valve for opening and closing communication through said passage; a float encircling said pump and guided thereby; connecting lever mechanism for opening and closing said valve by movements of said float; and a reservoir enclosing 45 said pump, valve, lever mechanism and float.
27. A pulsation pump of the vertical type for fuel supply comprising a piston spring actuated in the upward direction and adapted to be operated by pulsating pressure in the downward direction, a source of pulsating pressure in communication with the upper side of said pump piston, and means controlled by liquid fuel delivered by said pump 50 for controlling the communication between the source of pulsating pressure and the pump.
28. In fuel delivery apparatus a pump of the vertical type including a piston adapted 55 to be exposed on the upper side to the varying pressure of an internal combustion engine cylinder, and spring pressed in the downward direction, a reservoir into which fuel is pumped and means actuated by rise of fuel 60 in said reservoir for controlling connection between the pump and the engine cylinder.
29. A fuel supply system for internal combustion engines for automobiles comprising a reservoir from which fuel is supplied to the 65 carburetor by gravity, a passageway between said reservoir and a source of fuel supply, an outlet check valve controlling communication between said passageway and the reservoir, a pump of the vertical type within the 70 reservoir having the lower end of its piston chamber in communication with said passageway through an inlet check valve, a long helical spring in said lower end of the pump chamber normally urging the pump piston 75 upward, means of communication between the upper end of the piston chamber and the combustion chamber of a cylinder of the engine and means including a valve, valve lever 80 and float within the reservoir whereby the fuel in said reservoir controls such means of communication.
30. A fuel supply system for internal combustion engines for automobiles comprising a reservoir from which fuel is supplied to the carburetor by gravity, a passageway between said reservoir and a source of fuel supply, an outlet check valve controlling communication between said passageway and the reservoir, a pump of the vertical type within the 85 reservoir having the lower end of its piston chamber in communication with said passageway through an inlet check valve, a long helical spring in said lower end of the pump chamber normally urging the pump piston 90 upward, means of communication between the upper end of the piston chamber and the combustion chamber of a cylinder of the engine and means including a valve, valve lever and float within the reservoir whereby the fuel in said reservoir controls such means of communication.

Signed at New York City in the county of New York and State of New York this 18 day of March A. D. 1920.

WILLARD I. TWOMBLY.
